United States Patent Office

Des. 183,357

Patented Aug. 12, 1958

183,357

LOUD-SPEAKER OR SIMILAR ARTICLE

Theodore Lindenberg, West Islip, N. Y., and Raymond Spilman, Darien, Conn., assignors to Pickering Associates, Inc., Oceanside, N. Y., a corporation of New York

Application October 18, 1956, Serial No. 43,405

Term of patent 14 years

(Cl. D26—14)

FIG. 1

FIG. 2

FIG. 3

FIG. 4

FIG. 4

Fig. 1 is a front perspective view of a loud-speaker or similar article, showing our new design;

Fig. 2 is a top plan view thereof;

Fig. 3 is a side elevational view thereof; and

Fig. 4 is a rear perspective view thereof.

The ornamentation shown extends over the entire surface of the loud-speaker, excepting the base.

We claim:

The ornamental design for a loud-speaker or similar article, as shown and described.
